UNITED STATES PATENT OFFICE.

LOUIS WEIGERT, OF BERLIN, GERMANY.

INHALER FOR WARM AIR.

SPECIFICATION forming part of Letters Patent No. 398,991, dated March 5, 1889.

Application filed December 7, 1888. Serial No. 292,907. (No model.)

To all whom it may concern:

Be it known that I, Dr. Med. LOUIS WEIGERT, of Berlin, in the Kingdom of Prussia, and German Empire, have invented a new 5 and useful Improved Means for Warming Air to be Inhaled by Persons Suffering from Throat or Lung Complaints, of which the following is a specification, reference being had therein to the accompanying drawings.

10 This invention relates to apparatus for supplying heated air of a suitable temperature for inhalation by persons suffering from diseases of the throat and lungs.

The way in which I prefer to carry out the 15 present invention is represented in the accompanying drawings, whereof—

Figure 1 shows in side elevation the improved apparatus, Fig. 2 being a vertical section thereof to an enlarged scale.

20 The apparatus *d* and the burner *e*, or other source of heat, are respectively arranged to slide upon a rod, *a*, to which they may be clamped in the desired positions by means of the screws *b* and *c*. The apparatus *d* consists of an inner hollow cylinder, *f*, preferably made of sheet copper and open at the bottom, the top thereof being provided with a thin curved or arched lid or cover, *g*, furnished with two openings, *h h*, in which are 25 mounted two funnel-shaped tubes or flues, *i i*. The hollow cylinder *f* is provided with a flange, *k*, and stands upon an annular support, *l*, movement in a vertical direction being prevented by means of flat spring-blades *m*, hereinafter more particularly referred to.

30 Within the flange *k* of the hollow cylinder *f* is secured a second hollow cylinder, *n*, which forms a hood, open at the bottom and closed at the top by the lid or cover *p*. The hollow 35 cylinder *n* is furnished toward the bottom with a number of openings, *o*, through which air is permitted to flow into the apparatus. The lid or cover *p* of the hood *n* has three 40 openings, *q q* and *r*, through two of which (the openings *q q*) are passed the funnel-shaped tubes or flues *i i*, a funnel, *s*, being firmly mounted in the opening *r*. The hood 45 *n* is surrounded by a casing, *t*, of non-conducting material—such as asbestos pulp—

50 which serves to intercept the radiation of heat from the hood *n*, uniformity of temperature

of the air within the space *u*, formed between the hollow cylinder *f* and the hood *n*, being hereby better maintained. The spring-blades *m* press against the outer periphery of the 55 casing *t*, and the hood *n* being fixed within the flange *k*, the whole apparatus is firmly held upon the support *l*. In the funnel *s* is mounted an elbow-pipe, *v*, which conducts the air heated in the space *u* to the mouth-piece 60 *w* prior to inhalation by the patient. In the tube *x*, which projects from the elbow-pipe *v*, a thermometer, *y*, is fitted hermetically, and serves to indicate the temperature of the heated air. In order to prevent the patient, 65 after inhaling warm air from the space *u*, breathing into the latter and thus vitiating the air therein, the elbow-pipe *v* is furnished with suction and delivery valves. The conical valve *z*, which rests against the seat *w'*, 70 opens outwardly, and closes upon air being exhaled by the patient. The valve *z'*, which rests against the seat *v'* in the part *v'*, closes when inhalation of the heated air takes place and opens when air is exhaled. Thus, when 75 the air is being inhaled through the mouth-piece *w*, the valve *z* is open and the valve *z'* closed, and when air is being exhaled through the said mouth-piece, the valve *z* is closed and the valve *z'* open. To increase the sensibility 80 of the valves *z* and *z'*, they are made of very light material—such, for example, as aluminium—the valve *z* being placed in the horizontal branch of the elbow-pipe *v*, while the valve *z'* is arranged vertically, so as to open 85 automatically when the inhalation of warm air ceases. The pins *z* are employed to limit the movements of the valves *z* and *z'*.

When the apparatus is in use, the hollow cylinder *f* is heated by means of the burner *e* 90 or equivalent heating device, the products of combustion escaping through the pipes *i i*. The air drawn through the openings *o* into the space *u* becomes heated while flowing along the periphery of the hot cylinder *f*, and 95 after passing through the pipe *v* and the valve *z* is inhaled by the patient through the mouth-piece *w*.

What I claim, and desire to secure by Letters Patent of the United States, is—

100 An apparatus for producing warm air for inhalation, comprising a chamber, *f*, heated

by a burner, *e*, or equivalent heating device, fitted with outlets *i i* for the escape of the products of combustion and surrounded by a casing, *n*, the space *u*, intervening between the 5 chamber and the casing, serving as a passage for air which enters through openings below, becomes heated through contact with the central chamber, *f*, and ultimately escapes from the upper part of the space *u* by way of a con-

duit furnished with valves *z z'* for inhalation 10 and exhalation, respectively, substantially as described.

In witness whereof I have hereunto set my hand in presence of two witnesses.

LOUIS WEIGERT.
